UNITED STATES PATENT OFFICE.

WALTER JOHN LLOYD, OF BIRMINGHAM, ENGLAND, ASSIGNOR OF ONE-HALF TO WILLIAM PRIEST, OF BIRMINGHAM, ENGLAND.

CONTROLLING MEANS FOR EXPLOSION-MOTORS.

SPECIFICATION forming part of Letters Patent No. 752,627, dated February 16, 1904.

Application filed November 3, 1902. Serial No. 129,925. (No model.)

To all whom it may concern:

Be it known that I, WALTER JOHN LLOYD, a subject of the King of Great Britain, residing at Quadrant Cycle Works, Sheepcote street, 5 Birmingham, England, have invented certain new and useful Improvements in Controlling Means for Explosion-Motors, of which the following is a specification.

This invention consists of the improvements 10 hereinafter described in motors for motor-cycles and other motor road-vehicles of the kind in which the motive power is obtained by the explosion of an inflammable mixture of a highly volatile hydrocarbon and atmospheric 15 air, the said improvements having for their general objects to obtain greater efficiency in the said motors.

The improvement constituting the first part 20 of the said invention has for its object to avoid the resistance which is ordinarily offered to each outward stroke of the motor-piston, due to the compression of the air in the crank-case of the motor by the said outward stroke of the piston, and at the same time to remedy the 25 defect in ordinary motors due to the discharge of lubricating-oil through the several bearings in the sides of the crank-case, which discharged oil collecting on the outside of the 30 said case is readily picked up by the clothes of the rider.

In order that the said invention may be the 35 better understood, let it be noted that the ordinary motor has a pair of crank-plates, commonly called "fly-wheels," which rotate in a 40 crank-case containing a bath of lubricating-oil. The oil is picked up by the said fly-wheels, and by the centrifugal force set up by their rapid rotation is distributed into the engine-cylinder and onto the interior of the crank-case. In this way the engine-cylinder and the 45 several bearings in the sides of the crank-case are efficiently lubricated; but on each outward stroke of the piston the oil in the bearings of the crank-case is forced by the compression of air in the said case through the said bearings. Consequently there results a slow but 50 continual waste of the lubricating-oil, some of which sooner or later finds its way to the terminals of the electrical contact maker and

breaker of the ignition apparatus and so impairs the electrical contact of the two terminals when brought together that misfiring of the charge in the engine-cylinder frequently results.

The second part of the said invention has 55 for its object to render misfiring practically impossible from another cause hereinafter pointed out. In order that this part of the said invention may be the better understood, let it be noted that the ignition apparatus of 60 an ordinary motor has a plate-spring, commonly called the "trembler," which trembler carries a platinum point or stud constituting one of the terminals of the electrical contact maker and breaker. The platinum stud of 65 the trembler is on the compression-stroke of the piston forced by a cam on the spindle of the larger-toothed wheel of the two-to-one valve-gear of the engine into contact with a platinum-pointed set-screw constituting the 70 other terminal of the electrical contact maker and breaker. With this the ordinary arrangement the constant wear on the trembler-operating cam and on the trembler and on the platinum points results in the defect commonly 75 called "misfiring," which is remedied by the readjustment from time to time of the platinum-pointed set-screw. The object of this the second part of the said invention is to make the electrical contact of the terminals 80 independent of the wear of the parts of the ignition apparatus.

The third part of the said invention has for 85 its object to permit the vehicle to be driven directly by the engine at speeds below the normal speed, and thereby to render the employment of speed-reducing gear unnecessary.

I will describe my invention in connection 90 with the accompanying drawings, of which—

Figure 1 represents in side elevation a motor-bicycle, the motor of which is provided with the improvements constituting the said invention. Fig. 2 is a side elevation of the motor detached, drawn to a larger scale than Fig. 1, with the electrical terminals of the ignition apparatus in their break-contact position. Fig. 3 is a horizontal section on the dotted line X X, Fig. 2, showing one side only of the 95

crank-case and the crank-plate or fly-wheel adjacent to the said side. Fig. 4 represents a portion only of the motor with the electrical terminals in their make-contact position.

5 Fig. 5 is a similar view to Fig. 4 with parts removed for the better illustration of the means for reducing the power and speed of the engine below the normal power and speed.

The same letters of reference indicate the 10 same parts in the several figures of the drawings.

In carrying the first part of the said invention into effect an axial hole or air-passage *c* is made in the spindle *a* of the crank-plate or 15 fly-wheel *b*, (shown in Fig. 3,) so as to obtain free communication between the interior of crank-case *d* and the atmosphere at a point to which lubricating-oil cannot find its way in consequence of the centrifugal force set up 20 by the rapidly-rotating crank-plate or fly-wheel *b*. Thus it will be understood that as a free outlet for the air in the crank-case is provided no compression of air in the said crank-case takes place on each outward stroke 25 of the piston, and consequently there is no resistance to the outward strokes of the piston. Further, as compression of air in the crank-case is not effected there is no forcing outward of oil in the several bearings of the 30 crank-case *d*, and as oil cannot obtain access to the air-passage *c* in the spindle *a* in consequence of the centrifugal force of the crank-plate or fly-wheel *b* there is no waste of lubricating-oil in the crank-case nor soiling of the 35 exterior of the crank-case and parts carried by it.

In carrying the second part of the said invention into effect the parts of the ignition apparatus are constructed and arranged or 40 combined in the following manner: On a bush or annular projection *e* on the outer side of the crank-case *d* (see Fig. 5) a commutator-plate *f* is fitted, so as to be capable of an angular motion on the said bush *e*, the said commutator-plate *f* being turned through the connecting-rod *g* by the operating handle or lever *h* of the motor. (See Fig. 1.) On the said 45 commutator-plate *f* is pivoted a lever *i*, one arm of which bears on a gapped flange *k*, (see Fig. 2,) projecting from the front face of the cam *l*, by which the exhaust-valve lifter *m* is raised on alternate inward strokes of the piston. The other or free arm of the lever *i* carries the platinum stud *n*, constituting one of 50 the electrical terminals of the contact maker and breaker. The arm of the lever *i*, bearing on the gapped flange *k*, is pressed on the said flange by a spring *o*. When by the rotation of the exhaust-valve-lifting cam *l* the gap *p* in the 55 gapped flange *k* is brought under the projection on the end of the spring-pressed arm of the lever *i*, as is seen in Fig. 4, the end of the said lever being no longer supported by the flange *k*, the said lever *i* is turned under the 60 action of the spring *o* through a small angle, 65

and the platinum stud *n* is brought into electrical contact with the platinum-pointed set-screw *r*, constituting the other electrical terminal, as is represented in Fig. 4. The platinum-pointed set-screw *r* is screwed into a copper bar *s* on, but electrically insulated from, the commutator-plate *f*. To the bar *s* one of the electrical conductors *u* from the induction-coil is connected, as is illustrated in Figs. 2 and 4. On the gap *p* passing the end of the 70 spring-pressed arm of the lever *i* the said lever is turned in the direction proper for separating the two terminals *n r*, as in Fig. 2, and thereby breaking the electrical contact. By the making and breaking of the electrical 75 contact between the two terminals *n r* the electrical spark in the ordinary sparking plug in communication with the detonating-chamber of the engine - cylinder is produced and the compressed gaseous mixture in the said 80 cylinder fired. From an examination of Fig. 4 it will be seen that the projection on the spring-pressed arm of the lever *i* does not descend to the bottom of the gap *p* in the flange *k*. Consequently wear of the terminals *n r* does 85 not affect the certainty of their contact as in ordinary ignition apparatus, the projection on the end of the spring-pressed arm of the lever *i* descending farther into the gap *p* as the platinum points *n r* wear, and thereby compensating for the said wear. Further, as the 90 said points are not brought into contact by the rise and pressure of a cam which is subject to constant wear the readjustment of the set-screw *r* after its proper position has once 95 been determined is practically never required. 100

The timing of the sparking of the ignition apparatus is effected by the angular adjustment of the commutator-plate *f*, which is turned by the operation of the handle *h*, as is 105 hereinbefore described.

The reducing of the power and speed of the motor below the normal is effected by providing the commutator-plate *f* with a projection *t*, which when the operating-handle *h* 110 has been pressed forward into the position for driving at normal speed occupies a position immediately under the exhaust-valve lifter *m*. When the operating-handle *h* is pulled partially back toward its stopping position, the 115 projection *t* effects the partial lifting of the exhaust-valve lifter *m*, as is illustrated in Fig. 5. Consequently the exhaust-valve is partially 120 opened, and part of the power of the subsequent explosions in the cylinder being permitted to escape into the atmosphere the speed and power of the engine is reduced to the desired extent.

When the operating-handle *h* is pulled fully back for the purpose of shutting off the 125 power of the engine, the said projection *t* effects the opening of the exhaust-valve to its full extent.

The ignition apparatus on the exterior of the crank-case *d* is protected from dirt and 130

dust by a fixed box on the side of the said crank-case, which box is provided with a detachable cover *v*.

Having now described my invention, what I claim as new, and desire to secure by Letters Patent, is—

1. In a motor-cycle, the combination with an explosion-chamber; of a rotary cam, an exhaust-valve for said explosion-chamber, controlling means for said exhaust-valve actuated by said rotary cam, a rotary gapped flange, an angularly-adjustable commutator-plate adjacent to said gapped flange, means for operating said commutator-plate, a projection on said commutator-plate arranged to engage the controlling means for said exhaust-valve, a contact-point on said commutator-plate, a contact-lever pivoted on said commutator-plate and bearing at one end against said gapped flange, means for moving the contact end of said lever into engagement with said contact-point, when the opposite end thereof enters the gap in said gapped flange, and electrical connections between said contact lever and point, and said explosion-chamber.

2. In a motor-cycle, the combination with an explosion-chamber, of a rotary cam, an exhaust-valve for said explosion-chamber, a rod, actuated by said rotary cam for operating said exhaust-valve, a rotary gapped flange, a bush 30 adjacent to said gapped flange, a commutator-plate angularly adjustable on said bush, an operating-lever for moving said commutator-plate, a projection on said commutator-plate, arranged to engage the rod of said exhaust- 35 valve, a contact-point on said commutator-plate, a contact-lever pivoted on said commutator-plate and bearing at one end against said gapped flange, a spring for moving the contact end of said lever into engagement 40 with said contact-point when the opposite end thereof enters the gapped flange, and electrical connections between said contact lever and point and said explosion-chamber.

In testimony whereof I have hereunto set my 45 hand in presence of two subscribing witnesses.

WALTER JOHN LLOYD.
